UNITED STATES PATENT OFFICE.

SAMUEL H. THOMPSON, OF LOS ANGELES, CALIFORNIA.

TOOTHBRAH STERILIZER AND RETAINER.

1,278,789.

Specification of Letters Patent. Patented Sept. 10, 1918.

Application filed January 21, 1918. Serial No. 212,933.

To all whom it may concern:

Be it known that I, SAMUEL H. THOMPSON, a citizen of the United States, residing at Los Angeles, in the county of Los Angeles, State of California, have invented new and useful Improvements in Toothbrush Sterilizers and Retainers, of which the following is a specification.

This invention relates to a tooth brush sterilizer and retainer and it is an object of my invention to provide a retainer that will sterilize a number of brushes at the same time and yet not expose them to contamination from one another.

There are two ordinary forms of tooth brush retainers; in one the brushes are hung or in some manner suspended in the open air which allows them to be contaminated by dust and by proximity to other brushes; while in the other form a container or holder is provided for keeping the brushes away from the circulating air. When a container such as a glass or metal tube is used there is not a sufficient circulation of air around the brush to keep it from getting foul and unsanitary. My invention, however, provides a means by which a single brush or a plurality of brushes may be held and individually sterilized. The air in which each brush stands holds a vapor from a sterilizing fluid which keeps the brush from being contaminated in any way. The following detailed description will make clear the construction and also features of my invention.

In the drawings Figure 1 is a plan view of a typical form of my invention; and Fig. 2 is a section taken on line 2—2 of Fig. 1.

In the drawings 10 is the container into which the brush holding tubes 11 extend, said container being provided with brackets 20 by which it is mounted in a convenient place. At one end of the container 10 an opening 12 is provided with a tight stopper 13 (a hermetic seal), said opening being a convenient means by which the container may be filled with the necessary amount of sterilizing fluid. At the other end of container 10 is a cup 14 with a cover 15 (not necessarily tight) said cup being adapted to hold a tube of tooth paste or the like. The tops of the brush holding tubes 11 which extend down into the container 10 are made to fit tightly (hermeti-

cally) in tapered holes 16 in the top of said container and the tapered stoppers 21 fit tightly (hermetically) into the tops of tubes 11. Near the lower ends of tubes 11 are perforated partitions 17 upon which the tooth brushes rest. Enough sterilizing fluid is poured into the bottom of container 10 to cover the ends of tubes 11 without submerging partitions 17. The lower ends of tubes 11 which extend into the liquid are perforated with holes 19 thus admitting said liquid into the tubes. The vapors from the liquid pass through the perforations in partitions 17 thereby sterilizing and keeping the tooth brushes 18 in a perfectly sanitary condition.

No germs can reach one brush from another without passing through the liquid, because (in preferred form) the tube perforations are below the liquid level. But the disinfectant or sterilizer used is such that, even if the perforations were not submerged, the germs will be killed in passing from one tube to another through the vapors.

It will be readily understood that my device may be made with any desired number of brush holding tubes and of any suitable material, although clear glass is perhaps the most adaptable, pleasing and sanitary. If the device is made of glass or any similar material the tubes 11 can be made integral with the container 10. It is for these and other obvious reasons that I do not wish to limit myself to the particular form and construction described above. The particular construction shown in the drawings however makes it a very simple matter to clean the entire structure. By removing the tubes from the container 10 the inside of said container can be easily and thoroughly cleaned and when thus removed the tubes also may be easily cleaned. The opening 12 not only provides a very convenient way of filling the container but also provides a simple draining means. When it becomes necessary to change the sterilizing fluid the old fluid can be poured out through opening 12. If however said opening is not provided the fluid can be poured into the container 10 through one of the tubes 11.

I do not regard my invention as being limited to the specific construction, organization or arrangement herein described; but rather do I reserve to myself such changes, variations and modifications as may suggest

themselves to those skilled in the art or as may fall within the scope of the following claims.

Having described a preferred form of my invention, I claim:

1. In a device of the character described, a container adapted to hold a sterilizing fluid, a brush holding tube having a perforated partition near its lower end, there being holes in said tube below said partition, and a cover for said tube.
2. In a device of the character described, a container adapted to hold a sterilizing fluid, a plurality of brush holding tubes having perforated partitions near their lower ends, there being holes in said tubes below said partitions and cover means for said tubes.
3. In a device of the character described, a container adapted to hold a sterilizing fluid, a brush holding tube having a perforated partition near its lower end, there being holes in said tube below said partition, a cover for said tube, the container having an opening adapted to allow said sterilizing fluid to be poured into and emptied out of said container, and a cover for said opening.
4. In a device of the character described, a container adapted to hold a sterilizing fluid, a plurality of brush holding tubes hav-

ing perforated partitions near their lower ends, and having holes in said tubes below said partition, cover means on said tubes, an opening adapted to allow said sterilizing fluid to be poured into and emptied out of said container, and a cover for said opening.

5. In a tooth brush holder and sterilizer, a container adapted to hold a sterilizing fluid, said container having a plurality of brush openings in its top, a plurality of brush holding tubes fitted tightly into the top and extending down into the container with perforations in the lower ends of the tubes, perforated shelves in the tubes above the lower ends, and tight stoppers for the tubes.

6. In a device of the character described, a container adapted to hold a sterilizing fluid, a brush holding tube extending down into the container and having a perforated partition near its lower end to support the brush above the liquid in the container, the tube extending down below the partition and having an opening at its lower end adapted to admit liquid to the tube below the partition.

In witness that I claim the foregoing I have hereunto subscribed my name this 11th day of January, 1918.

SAMUEL H. THOMPSON.

Witness:

V. BERINGER.
